REMOTE INDUCTION HEAD FOR WELDING
THERMOPLASTIC PIPE

George P. Savko, 1051 Bernardo Ave., Sunnyvale, Calif.

Filed Aug. 5, 1963, Ser. No. 76,116

Term of patent 14 years

(Cl. D26—1)

Fig. 2

Fig. 5

Fig. 1

FIG. 1 is a perspective view of a remote induction head for welding thermoplastic pipe showing my new design.

FIG. 2 is a front elevation of FIG. 1 as seen from the left thereof.

FIG. 3 is a side elevation of FIG. 2 as seen from the right thereof on an enlarged scale.

FIG. 4 is a top plan view of FIG. 3.

FIG. 5 is an end elevation as seen from the right in FIG. 1.

I claim:
The ornamental design of a remote induction head for welding thermoplastic pipe, as shown.
